RENEWAL ELECTRIC FUSE PLUG

Evelyn Meltzer, Brooklyn, N. Y.

Application January 8, 1948, Serial No. 1,169

2 Claims. (Cl. 200—130)

1

My invention relates to improvements in renewal or refillable fuse plugs.

The major object of my invention is to provide an electric fuse plug of such design and construction wherein it is possible for the layman to remove the ruptured or burned-out fuse element and to insert a new element with ease and without the need or use of any tools.

Other objects of my invention are to provide a renewal or refillable fuse plug which is simple of design and construction, is inexpensive to manufacture, eliminates screws, rivets, soldering and the like for the replacement of the fuse element, simplifies assembly, is efficient in operation, and meets the requirements of the Underwriter's Code.

Another object of my invention is to provide a refillable fuse plug having such body design which simplifies the molding thereof and reduces mold costs, and especially lends itself to be cold molded from cold molding plastics.

For a better understanding of the invention, reference may be had to the following detailed description taken in connection with the drawing originally filed, in which

Fig. 1 is a side elevational view of the refillable fuse plug embodying the features of the present invention.

Fig. 2 is a sectional view taken on line 2—2 of Fig. 1, with the fuse element in place.

Fig. 3 is a fragmentary sectional view illustrating the manner in which the fuse element is inserted into the plug parts to renew or refill the same.

Fig. 4 is a fragmentary traverse sectional view taken on line 4—4 of Fig. 2.

Fig. 5 is a perspective view of the fuse element.

Referring now to the figures, 10 represents the main section of the body of the plug and 12 represents the secondary section of the body of the plug. These two sections are held together by a threaded metallic sleeve 11 which serves to retain and make contact with one of the terminals of the fuse receptacle. The body sections 10 and 12 are made from any electrical insulating material such as glass, porcelain, "Bakelite," etc., but preferably from cold molding plastic. 13 is a metallic spring like terminal bent hair-pin like at 15 and serves to grip and make contact with one end of the fuse element 16. The terminal 13 may be made from flat or round spring wire but preferably from semi-round bobby-pin wire. This terminal is held in position and secured between the parts 10 and

2

12. The terminal 13 connects with the threaded sleeve 11 through a soldered joint 14. The hair-pin like formation 15 of the terminal 13 serves to receive and retain in spring pressed relationship a removable fuse element 16. The said formation 15 eliminates the need of a screw or other means for securing the fuse element 16. The spring portion 15 springs outwardly to receive the element 16 which is inserted through an opening 17 in the part 12. A tight contact is thereby obtained. The fuse element 16 is weakened at 18 and when an overload of current is applied to the fuse, the fuse element will be severed at 18. The upper end of the element 16 is secured in position by being bent over the upper end of part 12 as indicated at 19 and is extended into a slot 20 of the part designed to receive the bent end 19. The orifice in part 12 is closed by a contact metallic cap 21 which is screw threaded onto the part 12 and is adapted to bear downwardly upon the upper end of the bent over portion 19 of the element 16 and thereby makes a secure contact with the element 16. The cap 21 serves as the second terminal in contact with the fuse receptacle. The cap 21 can be easily removed by hand, without the need or use of tools, to release the portion of the fuse element 16 which is left after the same has been severed and the hole 17 provides access to remove other portions which may still be in union with the hairpin portion 15.

While various changes may be made in the detail construction, it shall be understood that such changes shall be within the spirit and scope of the present invention as defined by the appended claims.

Having thus set forth and disclosed the nature of my invention, what is claimed is:

1. A fuse plug of the class described, requiring no use of tools for the removal or for the replacement of the fuse element, comprising a body made up of two sections and having an opening in each section, said sections arranged to retain securely in position a wire terminal extended across the openings, a wire terminal adapted to receive and hold securely without the need of a screw or the like one end of a fuse element, a removable terminal engaging with the opposite end of the fuse element and adapted to have engagement with a fuse receptacle contact, said removable terminal comprising a threaded cap which may be removed by hand.
2. A fuse plug of the class described, requiring no use of tools for the removal or for the replacement of the fuse element, comprising a

body made up of two sections and having an opening in each section, said sections arranged to retain securely in position a wire terminal extended across the openings, a wire terminal having a portion thereof bent hairpin like and adapted to receive and hold securely one end of a fuse element, a removable terminal engaging with the opposite end of the fuse element and adapted to have engagement with a fuse receptacle contact, said removable terminal comprising a threaded cap which may be removed by hand.
